UNITED STATES PATENT OFFICE

146,227

DESIGN FOR A WHEEL HOE

Joseph Mader, Chicago, Ill., assignor to Marmont Automotive Products, Inc., Chicago, Ill., a corporation of Illinois

Application November 20, 1945, Serial No. 123,942

Term of patent 14 years

(Cl. D35—2)

To all whom it may concern:

Be it known that I, Joseph Mader, a citizen of the United States, residing at Chicago, county of Cook, State of Illinois, have invented a new, original, and ornamental Design for Wheel Hoe, of which the following is a specification, reference being had to the accompanying drawings, forming a part thereof.

I claim:

The ornamental design for a wheel hoe, substantially as shown.

JOSEPH MADER.
